Samuel H. Jenkins,

BY A. M. Pierce.

ATTORNEY

UNITED STATES PATENT OFFICE.

SAMUEL H. JENKINS, OF NEW YORK, N. Y.

BUNG-BUSH WRENCH.

SPECIFICATION forming part of Letters Patent No. 291,197, dated January 1, 1884.

Application filed June 30, 1883. (No model.)

To all whom it may concern:

Be it known that I, SAMUEL H. JENKINS, of the city, county, and State of New York, have invented certain new and useful Improvements in Bung-Bush Wrenches, of which the following is a full, clear, and exact description, reference being had to the accompanying drawings, and to the letters of reference marked thereon.

10 My invention relates especially to wrenches employed for inserting bung-bushings such as described by me in an application filed April 23, 1883, and has for its object the provision of a wrench whereby the bushing may be easily and quickly screwed into the barrel.

15 My improved bung-wrench consists, essentially, of a metallic shank, one extremity of which bears one or more eccentric projections adapted and arranged to take against the shoulder or shoulders formed in the bush while screwing the same into the barrel. The extremity of the wrench whereon said projection or projections are formed is of such shape as to fit the interior of the bush. By use of a 20 wrench of this construction there is no outward pressure such as is necessarily exerted by the wrenches heretofore in use; but as the pressure is exerted in the line of movement of the bush in placing it in position, danger of 25 breaking the same while screwing into the barrel is obviated. Upon the extremity of the shank, opposite to the wrench, is formed a tap, adapted and arranged to cut a thread upon the edge of the hole wherein the bush is 30 to be inserted, and to sink the beveled flange at the outer extremity of the bush flush with the surface of the barrel. If desired, the cutter for forming the countersink may be located upon the shoulder of the wrench, just 35 above the eccentric projection. By cutting the thread in the barrel, the same being smaller than that upon the bush, said bush is inserted with greater facility than could be done without such thread, while by countersinking the 40 flange at the exterior of the barrel there is little danger of breaking the bush while driving home the wooden bung.

45 In the drawings, Figure 1 is a longitudinal

elevation of my improved bung-bush wrench. Fig. 2 is a cross sectional view thereof at line 50 $x x$ of Fig. 1, and Fig. 3 is a like view at line $y y$.

Like letters of reference, wherever they occur, indicate corresponding parts in all the figures.

55 E is the shank of the wrench, formed of suitable material, and provided with eccentric projections F, corresponding to the shoulders formed in the bung-bush.

G is a tap located upon the extremity of the shank, opposite to the wrench, designed for cutting a thread in the edge of the hole into which the bush is to be screwed.

H is a cutter or knife at the inner end of the thread, or at the shank above the eccentric projections F, or in both positions, adapted and arranged to form a countersink for the shoulder upon the bush.

I is the lever-handle, by which the tap and wrench are manipulated.

70 Having now fully described my invention, what I claim as new therein, and desire to secure by Letters Patent, is—

1. A bung-bush wrench consisting of a shank, whereon are located one or more eccentric projections, substantially as shown and described.

75 2. A metal shank having one or more eccentric projections at one extremity, forming a wrench, and a screw-cutting tap at the other, a handle being secured to said shank, and adapted and arranged to operate either wrench or tap, substantially as shown and described.

80 3. In a bung-bush wrench of the character herein specified, shank E, bearing one or more eccentric projections, F, tap G, cutter or cutters H, and lever-handle I, the whole combined and arranged to operate substantially as shown and described.

85 In testimony that I claim the foregoing I have hereunto set my hand in the presence of two witnesses.

SAMUEL H. JENKINS.
